UNITED STATES PATENT OFFICE.

LEO J. GOLDBERGER, OF NEW YORK, N. Y., ASSIGNOR TO L. WOHL & COMPANY, A CO-
PARTNERSHIP COMPOSED OF LEO J. GOLDBERGER AND LAZAR WOHL, BOTH OF
NEW YORK, N. Y.

GARMENT.

1,354,967.

Specification of Letters Patent.

Patented Oct. 5, 1920.

Application filed June 14, 1919. Serial No. 304,108.

To all whom it may concern:

Be it known that I, LEO J. GOLDBERGER, a citizen of the United States, and a resident of the city of New York, Far Rockaway, borough of Queens, in the county of Queens and State of New York, have invented a new and Improved Garment, of which the following is a full, clear, and exact description.

10 The object of the invention is to provide a new and improved garment more especially designed as an outer garment to be worn by children and arranged to permit of readily converting the garment into a bloomer dress, a bloomer romper or a dress. Another object is to permit of conveniently opening the garment, when worn, for sanitary purposes, without requiring removal of any one of the component parts of the 20 garment.

With these and other objects in view, the invention consists of certain novel features of construction, as hereinafter shown and described and then specifically pointed 25 out in the claims.

A practical embodiment of the invention is represented in the accompanying drawings forming a part of this specification, in which similar characters of reference indicate corresponding parts in all the views.

Figure 1 is a perspective view of the garment shown worn as a bloomer dress;

Fig. 2 is a rear perspective view of the same;

Fig. 3 is a front perspective view of the garment worn as a bloomer romper;

Fig. 4 is a rear perspective view of the same;

Fig. 5 is an enlarged perspective view of 40 a portion of the garment with parts in open position;

Fig. 6 is a similar view of the same with the parts in another position;

Fig. 7 is an enlarged sectional plan view 45 of the garment on the line 7-7 of Fig. 1;

Fig. 8 is an enlarged cross section of the garment on the line 8-8 of Fig. 2;

Fig. 9 is a similar view of the same on the line 9-9 of Fig. 2;

Fig. 10 is a similar view of the same on the line 10-10 of Fig. 1; and

Fig. 11 is a similar view of the same on the line 11-11 of Fig. 1.

The garment in its general construction 55 consists of a waist 20, a skirt 21 and a

bloomer 22. The waist 20 is open at the back and thus overlapping flaps 23 and 24 are provided adapted to be fastened together by suitable fastening devices 25 such as buttons and buttonholes. The waist 20 60 is further provided with a waistband having a front portion 30 and a back portion formed of two members 31 and 32, of which the member 31 forms an integral part of the front portion 30 while the member 32 is 65 fastened at its upper edge by stitches 33 to the back of the waist 20 and to overlie the inner member 31. The front waistband portion 30 of the waist 20 is provided with buttons 40; buttons 41 are attached to the 70 rear member 31; and back buttons 42 and side buttons 43 are attached to the rear member 32.

The bloomer 22 is provided with the usual 75 bloomer legs 50 and with a front waistband 51, and a back sanitary flap 52 having a back waistband 53. The front waistband 51 is provided with buttonholes 54 engaging the buttons 40 at the front waistband portion 30. The waistband 53 of the sanitary 80 flap 52 is provided with back buttonholes 55 engaging the buttons 41 on the waistband member 31 of the waist 20, and the said waistband 53 is provided with narrower side buttonholes 56 engaging the side buttons 43, as previously mentioned. Thus by 85 the arrangement described, the bloomer 22 is supported from the waist 20.

The skirt 21 is provided at the rear with a placket 60 and with a waistband 61 provided with front buttonholes 62, side buttonholes 63 and rear buttonholes 64. The front buttonholes 62 are adapted to be engaged with the buttons 40 (see Figs. 1 and 10) and the side buttonholes 63 are adapted 90 to engage the side buttons 43 (see Fig. 11), and the rear buttonholes 64 are adapted to engage the buttons 42 on the outer waistband member 32 of the waist 20 (see Fig. 8). Hence it will be seen that the front 100 portion of the waistband 61 overlies the front waist portion 51 of the bloomer 22, and the rear portion of the said waistband 61 overlies the waistband portion 32 of the waist 20. From the foregoing it will be 105 seen that the dress 21 is supported from the waist 20.

The sanitary flap 52 is detachably connected with the waist 20 wholly independent of the front portion of the bloomer or 110

the skirt 21 and hence the said sanitary flap 52 can be opened or closed without disturbing the fastening devices used for connecting the front of the bloomer with the waist 5 20 or the fastening devices connecting the skirt 21 with the waist 20.

It will further be noticed that the dress 21 can be entirely disconnected from the waist 20 thus providing a garment 10 composed of a waist and bloomer, thereby providing a bloomer romper. It will also be noticed that the bloomer can be detached from the waist with the skirt attached to the waist thus providing a dress. When the 15 waist, the bloomer and the skirt are connected with each other as described, a bloomer dress is provided.

Having thus described my invention, I claim as new and desire to secure by Letters 20 Patent:—

1. A garment, comprising a waist having a waistband made double at the back to provide outer and inner back members arranged in overlying relation one to the other, a 25 bloomer having a sanitary back flap detachably connected with the said inner member of the waistband of the waist, the front of the bloomer being detachably connected with the front of the waistband of 30 the waist, and a dress overlying the bloomer and detachably connected with the front of the said waistband of the waist and with the outer member of the back of the waistband of the said waist to allow of opening and 35 closing the said sanitary flap without disturbing the said dress.

2. A garment, comprising a waist open at the back and having a waistband made double at the back to provide an outer 40 member and an inner member the members overlying one the other, a skirt having a placket at the back and provided with a waistband detachably connected to the outside of the outer member of the said 45 waistband of the waist, and a bloomer having a sanitary back flap detachably con-

nected with the inner portion of the double back of the said waistband of the waist, the outer member of the said double back waistband overlying the attaching portion of the 50 said sanitary flap, the front of the bloomer being detachably connected to the front of the waistband of the said waist intermediate the skirt and waist.

3. A garment, comprising a waist 55 provided with a waistband having a single front portion and a double back portion forming the outer and inner waistband members arranged in overlying relation one to the other and of which the inner waistband member is an integral part of the front waistband portion, the said waist being open at the back, a bloomer having a sanitary back flap, means detachably connecting the said sanitary flap with the said inner waistband member of the waist, means detachably connecting the front upper end of the bloomer with the front waistband portion of the waist, and a skirt having a placket at the rear and provided with a waistband, 60 fastening means detachably fastening the back of the skirt waistband to the outer waistband member of the waist, the front portion of the waistband of the skirt overlying the front upper portion of the bloomer, 65 the said front portion of the waistband of the skirt having fastening members engaging the fastening means connecting the upper front portion of the bloomer to the 70 waist.

4. A garment, comprising a waist terminating at its lower end in a waistband made double at the back to provide outer and inner back members arranged in overlying relation one to the other, and a bloomer 75 detachably connected with the front of the said waistband and having a sanitary back flap detachably connected with the inner back member of the waistband and covered by the outer back member.

LEO J. GOLDBERGER.
